United States Patent Office

Des. 226,726

Patented Apr. 17, 1973

226,726

BEVERAGE WARMING STAND

Arthur Eckstein, Roslyn Heights, N.Y., assignor to
Chemex Corporation, New York, N.Y.

Filed Jan. 11, 1971, Ser. No. 105,758

Term of patent 14 years

Int. Cl. D7—04

U.S. Cl. D44—10 C

FIG. 1

FIG. 4

FIG. 3

FIG. 2

FIG. 1 is a perspective view of a beverage warming stand showing my new design;

FIG. 2 is a top view thereof;

FIG. 3 is a side elevational view thereof; and

FIG. 4 is a sectional view taken on line 4—4 of FIG. 1.

I claim:

The ornamental design for a beverage warming stand, substantially as shown.
